LOOM

Wayne F. Rossiter, San Francisco, Calif., assignor
to Independent Press Room Inc., San Francisco,
Calif., a corporation of California

Application April 29, 1935, Serial No. 18,710

2 Claims. (Cl. 139—55)

My invention relates to looms, and more particularly, to a loom formed from sheet material and adapted for the production of woven fabric suitable for small bags, purses, ties and like articles, where a woven fabric of relatively small size is desired.

Among the objects of my invention are: To provide a loom frame, shuttle and harness of sheet material; to provide such a loom wherein all the above named parts may be die-cut from sheet material by machine; to provide a cardboard loom; to provide a loom having a harness formed from a single piece of sheet material operable by hand to form a shed; to provide a loom which can be produced in quantity on modern die-cutting machines; to provide a loom having a harness formed of sheet material which will lie flat against the loom frame for shipment and thereafter can be bent into shape for use in forming a shed; to provide a cardboard loom having printed thereon a pattern; and to provide a cheap loom which can be manufactured by machinery in large quantities, the loom comprising the combination of a frame, harness, and shuttle, all cut from the same sheet material.

Other objects of my invention will be apparent or will be specifically pointed out in the description forming a part of this specification, but I do not limit myself to the embodiment of the invention herein described, as various forms may be adopted within the scope of the claims.

With the advent of a fashion calling for homespun bags and the like, small portable looms are to be desired, particularly when such looms can be imprinted with the various designs necessary in the weaving of such homespun articles. It is also particularly advantageous that such a loom be compact, be easily shipped and in order to make the loom attractive for sale, and cheap in construction. The loom of my present invention satisfies all requirements for such purposes and is so designed that it may be produced by modern die-cutting machinery, of strong rigid material, preferably cardboard, in large quantities. Quantity production makes for cheapness in manufacture. In the following specification, the word "cardboard" will be deemed to include all similar sheet material capable of being die-cut and it is also deemed that any sheet material, even metal, will be full equivalents with the scope of the appended claims.

The broad aspects of my invention as applied to the structure shown in the drawings may be more readily understood by reference to them in which Figure 1 is a perspective view of a pre-

ferred embodiment of the loom of my invention, strung up and having thereon a fabric partly woven.

Figures 2, 3 and 4 are various modifications showing how the warp threads may be attached adjacent the ends of the loom frame.

Figure 5 is a side view showing how the folding harness may be positioned flat and parallel to the frame.

Figures 6 and 7 show the two motions used to form a shed in weaving.

Figure 8 is a partial view in plan of a loom frame having a printed figure thereon.

Referring directly to Figure 1, a loom frame 1 is provided, preferably of cardboard of such a consistency that it will bend to some extent without breaking the fibers of the board. It is quite obvious that this frame may be of other sheet material, for example, such as bakelite, cloth-inserted bakelite, fibreboard, or even metal. Opposite ends of the loom frame are preferably provided with notches 2 whereby warp threads 4 may be strung across the frame.

As shown in Figures 3 and 4, I may prefer, in certain cases, to use other means to space the warp threads, and in Figure 3 I have shown V-shaped cuts 5 into which the warp thread may be inserted and in Figure 4 I have shown straight cuts 6 into the edge of the loom frame. There is very little to choose among the three methods and I may prefer different means to accommodate different sizes of warp material.

While stringing the warp threads 4 on the loom frame, they should be passed through apertures 7 in the heddle 8. This harness is preferably formed from a single sheet of the same material as the loom frame 1 and is provided on opposite ends with warp extensions 9, opposite extensions being offset so that alternate warp threads may be passed through the apertures 7 in the extensions on one end of the heddle, the remaining threads passing through the extension on the other end of the harness. The harness, to facilitate stringing and operation, is scored to provide two adjacent hinges 10 and 11 so that the harness may be folded upon itself, thus placing the extensions 9 closely adjacent. In this position, due to the fact that hinges 10 and 11 are both an equal distance offset from the mid-line of harness 10, no matter which hinge is uppermost, one set of extensions 9 will be raised and the other set depressed.

If, however, both hinges are partly flexed in order to place the apertures 7 in line and the flat surface 12 between the hinges in a horizontal

plane, the harness will be in a position most advantageous for stringing and the alternate passage of the warp threads through the apertures 7 will make the harness operative to form a shed 5 between the warp threads when fully flexed in either direction.

After the harness has been mounted upon the warp threads 4, the harness will also open to lie flat with the frame as shown in Figure 5 and 10 thus take up little space when not in use. The weft thread, usually of yarn, may be wound upon a shuttle 14, which is also die-cut, preferably from the same sheet as frame 1 and harness 8 and is provided with incurving notches 15 to 15 receive the hank of yarn 16. The end of the yarn is preferably anchored to the frame by means of a pair of tie holes 17.

In operation of the loom, the harness is taken between the thumb 19, and forefinger or middle 20 finger 20, and squeezed together until one side of the harness is raised and the other depressed as shown in Figure 6 where the harness end 21 is shown raised and the harness end 22 depressed, thus forming a shed 23 in the warp threads 25 through which the shuttle is then passed as shown in Figure 1.

After a single row has been woven, the positions of the thumb and forefinger are reversed, thus flexing hinges 10 and 11 and raising harness end 30 22 and depressing harness end 21, thus forming another shed in which the warp threads are crossed, whereupon the shuttle is passed through in the opposite direction. Alternate motions of the thumb and forefinger can then continue 35 with the passage of the shuttle at each reversal of the shed until the weaving is finished.

At any time during the weaving, however, the harness 8 may be used as a comb. The thumb and forefinger may be placed opposite each other, 40 thus making heddle surface 12 horizontal and bringing the apertures 6 into line. Movement of the heddle toward the work will then compact it, thus doing away with a separate comb for controlling the density of the fabric.

45 As will be seen from an examination of Figures 5, 6 and 7, the loom frame 1, when originally strung up is preferably flat. As the harness is operated, however, angles 24 formed by the operation thereof effectively shorten the warp 50 threads and my use of a flexible frame allows the frame to bend to form a belly 25, thus keep-

ing the warp threads taut at all times. This tautness effectively prevents the shuttle from catching in the warp threads as its passes through the shed and greatly aids in the speed of weaving.

As I prefer to print upon the frame 1 a design 5 26, it is obvious that when the design color changes other yarns 27 may be substituted for the original weft material and the design created by the sequency of the yarn colors, following the design layout.

The advantages of the loom described are obvious. By placing sheet material in roll or flat form in a press, the printing and the die-cutting may be done at the same time, and as all the 10 parts are from the same original sheet, cost is 15 reduced to a minimum.

If it is desired to make a loom of better grade 20 material, it is obvious that the loom can be made of different materials, even from those which are not suitable for forming hinges by scoring. In this latter case, harness parts 12, 21 and 22 are made as separate die cuttings and the hinges are formed by backing the parts with a flexible 25 material such as cloth, for example. In any case, however, I prefer to utilize materials which 30 will make the frame 1 of sufficient resiliency to keep the warp threads taut at all times.

It is of course to be understood that in case it 35 is desirable to reinforce the harness extensions or any other parts of the harness, that such reinforcement is deemed to be fully within the spirit of the invention as exemplified in the appended claims.

I claim:

1. In combination with the warp threads of a loom, a harness comprising a flat sheet of rigid material having offset extensions on each end thereof, alternate warp threads passing through a line of apertures in said extensions, and a double hinge formed in said harness parallel to the lines 40 of said apertures to provide relative motion of said extensions when said hinges are flexed.

2. In combination with a loom, a harness consisting of a single piece of sheet material, offset 45 extensions on opposite ends of said piece, said extensions being pierced to provide warp apertures, and a score mark on each side of the center line between said extensions whereby said piece may be bent at said marks to have a double hinge.

WAYNE F. ROSSITER.
